UNITED STATES PATENT OFFICE.

CHARLES W. GRUBB, OF SPRINGFIELD, ILLINOIS.

STAND FOR CAKE-BOXES.

1,356,620.

Specification of Letters Patent. Patented Oct. 26, 1920.

Application filed May 14, 1920. Serial No. 381,403.

To all whom it may concern:

Be it known that I, CHARLES W. GRUBB, a citizen of the United States, residing at Springfield, in the county of Sangamon and State of Illinois, have invented new and useful Improvements in Stands for Cake-Boxes, of which the following is a specification.

This invention relates to store furniture, particularly to stands or racks, and has for its object the provision of a stand adapted to hold a cake box of the type commonly provided with a glass front through which the contents may be seen, in such position that the contents may be easily visible to a prospective purchaser or to the salesman, the stand being furthermore so constructed that when the box is tilted forwardly the cover thereof will be automatically opened so as to permit ready access to the interior for the purpose of removing cakes or whatever is disposed in the box.

An important object is the provision of a device of this character which includes a stationary supporting stand and a box holding member pivoted within the stand and so constructed that a box may be readily engaged and held therein, this box holding member having in some respects the attributes of a clip or clamping device.

An additional object is the provision of a device of this character which will be simple and inexpensive in manufacture, highly efficient in use, durable in service, and a general improvement in the art.

With the above and other objects and advantages in view, the invention consists in the details of construction to be hereinafter more fully described and claimed, and illustrated in the accompanying drawings in which—

Figure 1 is a side elevation of my device showing the cake box in normal position,

Fig. 2 is a front elevation with the parts arranged as in Fig. 1,

Fig. 3 is a side elevation showing the box moved so that its cover is in open position.

Fig. 4 is a plan view of the box holding frame, and

Fig. 5 is a detail sectional view.

Referring more particularly to the drawings, I have shown my device as comprising a stationary supporting frame including spaced parallel base or foot members 10, uprights 11 rising therefrom, and upper and

lower cross pieces 12 and 13, respectively, connecting the uprights.

The movable portion of the device comprises a frame including arcuate strips 14 which are connected at one end with an inverted U-shaped wire frame 15 and which are connected at their other ends with a frame 16. The ends of the arms of the frames 15 and 16 are connected by substantially triangular pieces of sheet metal 17 which have their edges rolled about the arms of the frames. The structure is the same at both sides of the device and these triangular pieces 17 are connected by a bar 18 extending in spaced parallel relation above the lower cross piece 13 of the stationary frame. Secured upon the upper or bight portion of the rear frame 15 is a relatively long preferably wooden bar 19. The bight portion of the front frame 16 is formed with inclined sides 20 which approach comparatively close to each other and which merge into an upwardly bent rectangular loop 21 which has its upper portion bent forwardly, as shown at 22, to provide a handle. The material from which the frame 16 is constructed is somewhat resilient so that when a cake box, designated at A, is disposed within this movable member the box may be snapped into place, the loop member 21 springing sufficiently to permit this action.

Secured upon the confronting faces of the uprights 11 are open topped sockets 23 within which are removably engaged trunnions 24 carried by the ends of the bar 18 whereby the box and its support will be pivoted with respect to the stationary frame.

Projecting from the arcuate strips 14 are spaced pins 25 and 26 engageable respectively against the front and rear edges of the uprights 11 for limiting swinging movement of said movable member, as clearly shown.

The box A is of a type well known and is provided with a hinged cover B having a rolled or beaded edge C. A very important feature of my invention is the provision of pins 27 which project from the confronting faces of the uprights 11 and which are disposed at such a location that when the box is tilted forwardly these pins 27 will engage the cover B and open it or rather hold it stationary while the box moves which is in effect the same thing.

In the use of the device the operator engages the rear edge of the box between the triangular plates 17 and then forces the front edge of the box downwardly to cause it to snap into place behind the loop 21. When the device is in normal position it will be arranged as shown in Fig. 1, and if the box is of the type which has a glass front the contents will be advantageously displayed. When the salesman wishes to remove any of the contents it is not necessary that he open the cover manually as it is merely necessary that he tilt the movable part of the box forwardly as by grasping the loop 21 whereupon the cover will automatically open. When the movable portion is returned to normal position the cover will close gravitationally.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A device of the character described comprising a stationary upright rectangular

frame, a movable frame pivoted within the lower portion thereof and adapted to hold a cake box with a hinged flanged cover, pins projecting from said movable frame and engageable with the sides of the upright frame for holding the box in normal position, and pins projecting from the confronting faces of the sides of the upright frame and engageable with the flanges of the cover whereby to open the latter when the box is swung.

2. A device of the character described comprising an upright rectangular stationary frame provided with supporting feet, sockets carried by the confronting faces of the sides of said frame at the lower ends thereof, a movable frame adapted to carry a cake box and provided with trunnions removably engaged within said sockets, pins projecting from the sides of said movable frame and engageable with said upright frame whereby to limit pivotal movement of the swinging frame and box, and other pins carried by the upright frame and engageable by the cover of the box whereby to open said cover when the box is tilted forwardly.

In testimony whereof I affix my signature.
CHARLES W. GRUBB.
